UNITED STATES PATENT OFFICE.

ISAAC SPRINGTHORPE, OF PHILADELPHIA, PENNSYLVANIA, ASSIGNOR, BY MESNE ASSIGNMENTS, TO SPRINGTHORPE TEXTILE MACHINE COMPANY, OF PHILADELPHIA, PENNSYLVANIA, A CORPORATION OF DELAWARE.

WARP-KNITTING MACHINE.

Application filed June 28, 1918. Serial No. 242,480.

This invention relates to improvements on the knitting machine set forth in my Patent No. 1,165,294, dated December 21, 1915, and, more particularly, to the operating and controlling mechanism for the needle bar, a safety tension means for the warp threads, the pattern chains, and the pattern chain supports.

In my patent aforesaid the needle bar moves only transversely to its length, subject to the joint control and actuation of two instrumentalities or mechanisms, operated from the same power shaft, one mechanism, a cam, actuating and timing the horizontal movement of the needle bar, and the other mechanism, an eccentric, actuating and timing its up and down movement and dwell. The rise and fall of the needle bar, is, in that machine, determined by the shifting of the cam rails having adjustable cam plates, the cams and cam plates cooperating with the needle bar. This operating mechanism is capable, as stated in my patent, of different adjustments to cause the needle bar to travel in different predetermined paths, according to the nature of the fabric to be knitted. In fact, in the use of that machine it has been customary to so form and adjust the cam rails and their plates as to cause the needle bar to move horizontally when advancing and also for a short distance as it began its return movement. This horizontal movement in both directions enables the thread guides to place threads both forward and back of the needles, if desired, and then to utilize the oblique movement to return the needles to the lowest, or starting, position for the purpose of casting the loops from the bases of the needles over the loops held in the needle hooks.

That part of the present invention which relates to the operation and control of the needle bar has for one of its objects the provision of improved means whereby more accurate and exact operation and control of the needle bar and a great increase in the speed and capacity of the machine are obtained.

50 This improved means can be arranged to not only cause the needle bar to travel in any predetermined cycle such as was possible with the cam rails of the machine of

my patent but it can also be set to cause the needle bar to move solely in an oblique path. 55 This movement being the shortest one possible, the speed of the machine and its production are greatly increased over the speed and output of the machine of my patent. The improved operating means enables the 60 needles to intercept the previously shifted or laid warp threads near the end of the first half-cycle of the needle bar movement and also at the beginning of the second half-cycle. The utilization of this simple 65 and direct oblique movement is feasible in knitting fabrics requiring the use of part, or the full, complement of thread guide bars, since the eyes of the thread guides can be closely assembled in parallel rows in position to be intercepted by the needles during the oblique movement of the needle bar whether the latter is advancing or receding.

The improved mechanism for operating the needle bar also enables the latter to 75 be moved in a path corresponding to a right angle, i. e., first upwardly, then horizontally advancing, then returning horizontally, and finally moving downwardly, covering the same path as that of its advance and entirely omitting any oblique movement.

By way of illustration, I have indicated two paths of travel, or, cycles of movement of the needle bar under the control and actuation of the improved needle bar operating means, wherein the return movement is along the same path, but in a reverse direction, to the path traveled by the needle bar on its advancing movement. It is to be 85 understood, however, that the improved needle bar operating means enables the needle bar to be moved in any one of an almost unlimited number of paths as the resultants of different predetermined individual and relative adjustments of the said improved means, so that laces, nets, fabrics, and cloths in an almost infinite variety can be produced at different times.

95 My improvements in this respect consist in the elimination of the cam rails and adjustable cam slides of my patent, and the use of rockers, arms, or levers, directly cooperating with the needle bar, preferably by the use of grooved or slotted parts in 100 the rockers which receive rollers carried by

the needle bar, and the direct actuation of the rockers from the same power shaft which causes horizontal shifting of the needle bar. The rockers are actuated by a cam on the power shaft which gives them the desired dwell at the proper points to prevent further rising or falling of the needle bar at certain parts of its travel, these points of dwell of the needle bar being dependent on the resetting of the cam on the power shaft, relatively to the arrangement of the eccentric thereon which is used to impart horizontal movement to the bolsters and the needle bar. The eccentric which controls the horizontal shifting of the bolsters, and hence the needle bar, may be taken off and a cam substituted, to afford a dwell of any desired duration and at any desired point of the horizontal travel of the bolsters, and used at the same time with the cam which controls the movement of the rocker arms. The relative arrangement of the eccentric and cam, or the two cams, on the power shaft permits of any desired cycle of movement of the needle bar, with horizontal and vertical travel and dwells where desired, or, a cycle embodying an oblique path only, with dwells as desired, to enable the thread guides to place the threads, according to the action of the pattern chains, across the hook sides, and the backs, of the needles so that the knitting of any one of an almost infinite variety of laces, nets, fabrics and cloths may be carried on. The use of rockers directly cooperating with the needle bar, and the direct connection of the rockers with the cam on the power shaft enables such minute adjustments to be made and the establishment of such relationships of the two operating mechanisms which control the needle bar, that results are obtainable which even the mechanism of my patent aforesaid cannot produce.

To enable the braking action on the warp beams to be made as heavy as needed to afford a firm fabric where firmness is desired, and yet safeguard against snapping the warp threads by sudden tensions due to needle pulls, I have devised a safety tension device which relieves the threads from any tendency to snap when there are sudden pulls. This device embodies spring-floated or spring-suspended rods over, or against which, the warp threads run intermediate the warp beams and the thread guides. Such safety tension devices may be variously arranged but, preferably, comprise rods having detachable or snap-hook connections with coil springs which are, in turn, connected to the upper frame work or rack arms of the machine. The springs compensate for the additional tension to which the threads are liable when subjected to sudden needle pulls. This part of the invention is not limited to

the use of rods or to snap hooks, but comprises spring tension means for the purpose set forth.

That part of my present invention which relates to the pattern chains and their supports, has for its object to simplify them, obviate the use of adjustable supports for the chains, and eliminate the extra driving lugs, rendering the placing of the chains on the drum and their removal therefrom a much easier and quicker operation, besides insuring proper engagement of the chains with the drum and their being driven thereby at all times without possibility of becoming entangled. To that end there are provided guides or supports over or against which the free parts of the pattern chains hang by gravity, the weight of said chains keeping them in engagement with the driving drum and the guides at all times and yet permitting easy removal or placement of the chains. Means, such as an idler, prevents the free hanging parts of the chains from interfering. Only one set of notches is provided in the annular ribs of the drum to receive the heads of the pivotal connections between the links of the chains. The guides or supports may be rotatable, or they may be stationary, both forms being shown and described.

Further improvements over the machine of my Patent No. 1165294, comprise, first, a supplemental frame located intermediate the end frames of the machine and adapted to support the warp thread cross rods; second, combining the thread guide bar hanger brackets of the end frames with the steadier pin plates; third, providing supplemental thread guide bar brackets adapted to be hung from the warp thread cross rods to serve as additional suspending means for the thread guide bars.

In the accompanying drawings:—

Fig. 1 is a view in elevation of the right end of the machine;

Fig. 2, a similar view of the left end of the machine;

Fig. 3, a vertical sectional view through the center of the machine locking in the same direction as Fig. 2;

Fig. 4, a rear fragmentary sectional elevation on the line 4—4 of Fig. 1;

Fig. 5, an enlarged fragmentary horizontal sectional view of the right-hand end of the machine on the line 5—5 of Fig. 1;

Fig. 6, an enlarged fragmentary vertical sectional view of the right-hand end of the machine on the line 6—6 of Fig. 5;

Fig. 7, a vertical sectional view on the line 7—7 of Fig. 6;

Fig. 8, a horizontal sectional view on the line 8—8 of Fig. 4;

Fig. 9, an enlarged fragmentary side elevation showing a pattern chain, its drum, and the pattern chain guide;

Fig. 10, a detail plan view of a portion of the pattern chain drum and chains;

Fig. 11, a fragmentary view in elevation illustrating the relative position of the thread guides and needles, the threads being shown as leading downward from the guide eyes across the path of the needles and down to the finished work below;

Fig. 12, a diagrammatic view showing the 10 first, or lowest, position of the needles, needle bar, and work plate with relation to the thread guides;

Fig. 13, a similar view showing the second 15 relative position of the needles, needle bar, work plate and thread guides, the needles having fully advanced past the thread guides, and the needle bar cycle being half completed;

Fig. 14, a similar view showing the needles 20 in return transit past the rows of thread guides;

Fig. 15, a similar view showing the needles, needle bar and work plate returning to the position shown in Fig. 12;

Figs. 16, 17, 18 and 19, show diagrammatically certain of the paths which may be described by the point of a needle, according to the adjustment of the needle bar controlling and actuating mechanisms;

Fig. 20, a detail side elevation partly in section, similar to Fig. 9, showing a modified pattern chain idler;

Fig. 21, a detail front view of only the idler of Fig. 20;

Fig. 22, a detail elevation of an intermediate frame member, and

Fig. 23, a detail elevation of a combined yoke and thread guide bar supporting plate.

A represent supporting end frames connected by cross sills B to form the foundation on which the superstructure or machine proper rests. The upper or machine frame embodies end frames D whose feet 10 are supported by the sills B; a superstructure 45 comprising duplicate parts 11 having forwardly extending rack arms 12 and rearwardly extending rack arms 13, tie rods 14 and tubes 15 respectively connecting the side frames D; and tie rods 16 (Fig. 1) joining the superposed rack frames 11. At the front of the machine is the main or drive shaft 17 mounted in the bearings 18; the rock shaft 19 mounted in bearings 20; and a second rock shaft 21 mounted in bearings 22. The 55 main shaft 17 carries a bevel pinion 23 which meshes with a larger bevel gear 24 carried on a pattern chain drum shaft 25, this latter shaft being mounted in bearings 26 located on supporting brackets 27 which are secured to main frame D by bolts 28.

The rock shaft 19 is actuated by an eccentric 29, comprising a disk 30 having a hub 31 and set screw 32 by which it is secured on shaft 17, and a triple slotted eccentrically 65 adjustable disk 33 secured by bolts 34 to the

disk 30 to revolve therewith. Surrounding disk 33 is the two-part strap 35—36, part 35 having a channelled extension 37, to which is bolted connecting rod 38, the latter being jointed by stud 39 to an arm 40 which has hub 41 fastened to rock shaft 19 by set screw 42.

Securely bolted to the frames D are the horizontal rails 43 (Figs. 1, 2, 3, 4) on which bolsters 44 are adapted to slide. Secured to rock shaft 19 by set screws 45 are arms 45. Two-part adjustable connecting rods 46 are joined to the bolsters 44 by studs 47 and to the arms 45 by pivotal connections 48. Each bolster comprises a top piece or slide 49 (Fig. 6), a lower retaining plate 50, and a work plate supporting bracket 51 cast integrally with the bolster 44 and the needle bar guide bracket 52 to which the spaced vertical guides 53 and 54 are suitably connected by bolts 52' (Figs. 5, 6). The work plate 143 is connected to brackets 51 for vertical adjustment by slots and bolts 51' and elevating screws 51'' (Figs. 5, 6, 7).

The needle bar 55 carries on its rear face a series of detachable lead blocks 56 into which the needles 57 are molded, as usual. Secured to the ends of the needle bar at 58'' are the standards 58 to which the vertical slides 59 are fastened at 59'. The slides 59 are adapted to move up and down between the vertical guides 53 and 54. Except the connection constituted by vertical guides 53 and 54 and vertical slides 59, the needle bar 55 has no connection with the bolster 44. It will be seen that the needle bar 55 is slidable horizontally on the rails 43 and vertically with the slides 59.

Rock shaft 21 is actuated by a slide cam mechanism consisting of the cam 60 secured to main shaft 17 by hub 61 and set screws 62 and provided with channel 63. A guide block 64 is loosely bushed on main shaft 17 and there is a rectangular open yoke 65 which is slidable on guide block 64 and carries cam roller 66 which travels in channel 63 of cam 60. A connecting arm 67 is slidably fitted in the channeled lower end of the yoke 65 and is secured to the lower end thereof by bolts 65' after it has been longitudinally adjusted by screws 67' to give the arm the requisite length for effecting the proper vertical movement of the needle bar and is in turn secured to the free end of levers 68 on rock shaft 21 at 67''. Secured on the end portions of the rock shaft 21 are lifting levers or rockers 69 which have slots or guides 70 receiving cam rollers 71 carried by the lower ends of the needle bar supporting bracket carriers 58', the latter being bolted to the ends of the needle bar 55.

Bolted at 72' to the horizontal members 72 of the frames D are guide bar hanger brackets 73 having vertical grooves 74 in their opposite faces for the reception of the 130

vertically slidable adjustable hangers 75. Each thread guide bar 76 is provided at its ends with vertical lugs 77 (Figs. 4 and 8) carrying pins 78 and 79 which are horizontally slidable in the depending ends of hangers 75 and suspend the bars 76 from said hangers. The pins 78 are longitudinally adjustable in the lugs 77 by the provision of a threaded end and lock bolts 80 and after being set are adapted to move as a unit with the thread guide bar 76.

Also attached to the right hand frame D (Figs. 1 and 4) above yoke 73 is an arched standard 81, having an arcuate slot 82 in which steadier pins 83 are adjustably mounted and which pass through slots 84' in the upper ends of steadiers 84 secured to the right hand ends of thread guide bars 76. By pivotally supporting the thread guide bars 76 on the pins 78 and 79 and properly adjusting the steadier pins 83, the free ends of the thread guides 85 may be set in spaced or in close proximity to each other, the steadiers 84 also providing against lateral displacement of the thread guides 85 should there be any undue tension on the thread guides during the knitting processes. It will be seen that the pins 78 and 79 are movable longitudinally in the hangers 75, and that the slotted ends 84' of steadiers 84 slide freely on the steadier pins 83.

The yoke 72-73 and arched standard 81 may be formed in a single piece as shown at 81' in Fig. 23.

The thread guide bars 76 are adapted to reciprocate in fixed paths once they have been arranged to knit a given fabric by selectively arranged pattern chains (Figs. 4, 8, 9 and 10) operated by a pattern chain drum 86. The chains comprise alternate plain disks 87 and notched disks 88 secured to and revolving with pattern chain drum shaft 25 which is turned from main shaft 17 by gears 23, 24. The various pattern chains necessary to produce any desired longitudinal movement of the respective thread guide bars 76 are selectively assembled as to sequence and character of links according to the pattern of the fabric which is to be knit. Preferably, each thread guide bar 76 will be operated by only one pattern chain.

The pattern chains are formed of flat links 89 selectively and detachably articulated by removable screws, bolts or pins 90, the ends or heads 91 of which project into notches 92 in the disks 88 whereby the chains are driven simultaneously with the drum 86. Preferably, the heads 91 of succeeding fastenings project in opposite directions.

In Fig. 9 there is shown an improved support or idler for the pattern chains. This comprises an idler drum or a set of independent idler disks 93 having notches 94 each revoluble freely on a horizontal shaft 95, the ends of which are supported by bearings

95' secured to the chain drum supporting brackets 27. The respective disks 93 are in vertical alignment with the corresponding notched disks 88 on chain drum 86 and their notches are adapted to mate, whereby the screws, bolts or pins 90 which connect the chain links are caused to remain within the notches 92 a sufficient length of time to move the chains simultaneously and accurately. With the auxiliary drum in place it has been found unnecessary to provide other support or guiding means for the chains, and they may be allowed to freely hang downward. The outer stretches of the chains run over an idler roller 27' to keep them from becoming entangled with the inner stretches thereof.

In lieu of the idler disks 93, a multi-channeled idler 96, shown in Figs. 20, 21, which is carried by the brackets 27, may be employed. The pendant parts of the chains 89 lie in the respective channels 96' and freely slide therein, as the drum 86 turns, the webs 96" preventing interference between the respective chains.

To directly actuate the thread guide bars longitudinally by the pattern chains, there is provided a series of horizontal slides 97, one for each pattern chain and thread guide bar, said slides being movable longitudinally within guideways 98 in the bracket 99 (Figs. 4 and 8). Each slide 97 carries a roller 100 at one end to contact with the chain links 89 and its opposite end abuts the end of the pin 78 attached to the left hand end of the thread guide bar 76 to be actuated. The slides 97 thus become direct media through which any given thread guide bar 76 is shifted lengthwise of itself to an extent corresponding exactly to the profile of each link in the pattern chain which controls that particular thread guide bar. To insure continuous contact between the pin 78 and the end of slide 97, as well as between roller 100 and chain link 89, Figs. 4 and 8, tension springs 101, one for each thread guide bar, are attached directly to the ends of thread guide bars 76, while the opposite ends of the springs are secured to a rod 102 mounted on chain drum brackets 27. Thus the movement of the thread guide bars 76 will at all times conform accurately to the conformation of the surface of the adjacent chain link 89, even when great variation in height is necessary to knit special laces or fabrics.

Depending from near the center of the horizontal frame rail 103 of each frame D are the brackets 104 (Figs. 1, 2, 3) held in place by bolts 105 and having vertical slots or guideways 106 in which the bearing blocks 107, 108 and 109 are free to move vertically. These blocks carry the gudgeons 110, 111 and 112, respectively. Attached to the right hand frame section D by an adjustable slot and bolt connection 113' is the

bracket 113 having bearing 114 in which is mounted the shaft 115 carrying at its outer end a ratchet wheel 116 and at its inner end a gear 117 meshing with the gear 118 on 5 gudgeon 110. In vertical alignment on gudgeons 110, 111 and 112 are the intermeshing driving gears 119, 120, 121, respectively. On the right hand end of rock shaft 21 is loosely mounted a triple lever 122 having the long 10 slotted arm 123 and the shorter arms 124 and 125. The two latter arms carry the gravity or spring actuated dogs 126 and 127, respectively, the free ends of which engage the teeth of wheel 116. An eccentric 128 15 mounted on main shaft 17 actuates adjustable connecting rod 129, the lower end of which is bolted to the slotted arm 123 of the triple lever 122.

The take-up rolls 130, 131 and 132 are 20 caused to revolve at the same speed by gears 119, 120 and 121, and one or more of the rolls may be sanded or otherwise roughened to insure a firm grip on the finished work.

Warp beams 133, brake straps 134 and 25 weights 135 are used to prevent the warp beams from unwinding the warps too fast when a sudden pull is exerted by the needles in engaging the threads presented by the thread guides.

As a means for relieving sudden tensions 30 caused by needle pulls, there is provided an improved safety tension device comprising coiled springs 136 connecting wire strands 137 stretched between the rack frame members 11 (Figs. 2, 3, 4). The springs 136 support warp cross rods 138, the latter being attached to the springs by any desired detachable means such, for instance, as snap-hooks 139. When a sudden pull is 40 given the warp thread 140, the tension is lightened and compensated for by the springs 136 which yield to absorb it. A tighter brake may, with this safety tension device, be used on the warp beams 133, permitting the knitting of a firmer fabric than 45 would be possible if there were no provision against snapping the threads by sudden tensions.

Mounted on the upper side of yokes 73 50 and fastened thereto by screws 147 are the warp cross rod supports 147 (Figs. 1, 3, 4), in the ends of which warp cross rods 148 are mounted. These rods act as guides for the warp threads 140 on their way from warp beams 133 to the thread guides 85 and separate the threads passing through each row of thread guides from those passing through the other rows.

The path of each warp 140 is from the 60 warp beam 133 across the spring tension rod 138, over the warp cross rods 148, through the thread guide 85, into engagement with the hook and also the shank of the needle 57, thence downward in front of the take-up rolls 130, 131, 132, around roll

130, passing between rolls 131 and 132, over and back of roll 132, and finally downwardly back of the take-up rolls into the basket beneath.

Instead of supporting the thread guide 70 bars 76 at their ends and providing steadiers 84 at one end only, an additional intermediate frame E may be used, as shown in Fig. 22, for supporting and steadyng guide bars 76 near the center of the machine. This 75 intermediate frame E is provided with feet 150 having bearing blocks 151 and 152 which clamp the frame supporting tubes 15, thus making the frame E an integral part of the larger machines of this type. The main 80 shaft 17 is supported in bearings 153 and there are bearing 154 and 155, respectively, for rock shafts 19 and 21. The upper part 85 of intermediate frame E is secured to the side frames 157 and 158 by bolts 159 passing through slots 160. Adjusting screws 161 threaded through lugs 162 and having lock nuts 163 may also be used. Holes 164 receive the warp cross rods 148 and set screws 165 hold them in place. When the intermediate frame E is used, 90 additional standards like those shown at 73 may be mounted thereon to support intermediate thread guide bar hangers like the hangers 75 with additional thread guide bar support pins like the pins 78 inserted in extra lugs like the lugs 77 near the center of the thread guide bars 76. Also, one or more hanger plates substantially like that shown in Fig. 23 but having individual holes and set screws for the warp thread bars may be suspended directly on the warp cross rods 148, thus utilizing these rods as the intermediate guide bar support, with lugs 77, support pins 78 and hangers 79 similar to those already described. In machines of more than ordinary length it has been found advisable to place additional steadiers like those shown at 84 at the left end of the guide bars, with steadier pins like those shown at 83 carried by a second arched standard like the standard 81 or by the combined yoke and standard 81', Fig. 23.

During its travel each thread is actuated, controlled and guided in several ways, i. e., first, by the tension applied to the warp beams 133 by the brake strap 134 and heavy or, light weights 135; then by the device 136-139 to prevent breaking of the thread under sudden tension increases; then, under the control of the pattern chain, the thread guide places the thread in proper position; next, either the hook or opposite side of the needle engages the thread (thus either forming the thread into loops, chains, nets, etc., or else aiding in placing certain threads in position to be woven in by certain other threads), and during these operations the tension rolls 130-132 are exerting 115 120 125 130

5 a continuous, though indirect pull on the thread from the moment it leaves the warp beam until the knitted fabric is wound around the rolls themselves.

5 The knitting of any particular pattern or design is accomplished by proper regulation and adjustment of all the actuating and controlling devices. Any warp beam may be retarded by high brake tension in order to cause its threads to enter the fabric in close, short loops; or, again, a warp beam may be almost entirely freed of tension in order to permit its threads to form long, loose loops either within the fabric proper, or, as a 15 nap on the surface. The tension relief or compensating device guards against breakage and also regulates any unevenness of thread pull. The guiding of the threads lays the foundation and also the pattern or 20 design, and has to do with the lateral elasticity or firmness of the fabric. The needles, in conjunction with the latches, latch wire and work plate, do the actual knitting in of the threads placed by the guides. The 25 take-up rolls not only pull the finished work away from the needles but also enable the latter to pull down from the warp beams thread or yarn of proper lengths to knit the design or pattern of lace or other fabric. 30 It will be seen that when an extreme movement of a thread guide bar takes place in either direction, an increased length of thread must be taken from the warp beam, and then the needles do the pulling in of 35 the threads, while the take up rolls not only hold fast to what they have pulled in but they are, at the same time, by their continued revolution pulling the threads past the needles. It must be remembered, however, 40 that the take up tension is at all times subject to the attachment of the threads to the shanks or hooks of the needles so that the greater tension is exerted at and below the needles, and less tension exists between 45 the needles and warp beams.

The needle bar 55 being supported by the slotted lifting levers 69 carried by rock shaft 21, is actuated vertically by movement imparted to rock shaft 21 by cam 60 50 and intervening connections heretofore described. Vertical movement of the needle bar is, however, subject to the horizontal position of the vertical guides 53 and 54 forming part of the horizontally movable 55 bolsters 44. Now, since the bolsters 44 are movable horizontally on the rails 43 when actuated by eccentric 29 and rock shaft 19, vertical guides 53 and 54 being attached to bolsters 44 will serve to move guides 59 and 60 also the needle bar 55 in a horizontal direction.

Having thus provided independent actuating mechanism for moving the needle bar 55 either horizontally or vertically, it is subject to independent vertical and horizontal

movements, or, to travel in a path which is the resultant of those movements. Consequently the eccentric 29 and cam 60 may be set in such relation to each other on main shaft 17 as to move the needle bar 55 horizontally forward at the same time that it moves vertically upward. The resultant of the horizontal and vertical movements produces a direct diagonal movement of the needle bar 55 similar to the diagram in Fig. 75 18. In like manner, the mechanism may be set to return the needle bar 55 vertically downward simultaneously with a horizontal movement backward, thus producing an oblique movement in the same plane with the 80 previous diagonal movement.

The channel 63 of the cam 60 lies in the arc of a circle struck from shaft 17 for approximately one-half the revolution of the cam; hence the roller 66 remains at a fixed 85 distance, or "dwell" from shaft 17 during approximately one-half of a machine cycle (i. e., one revolution of shaft 17) as, for instance, after the needles have risen and passed through the thread guides toward 90 the front of the machine to a position substantially corresponding to that of Figs. 3 and 13. The roller 66 then describes an eccentric path in channel 63 at varying distances from the center of shaft 17 during 95 the remaining half of the machine cycle. The effect of this conformation of channel 63 is to cause needle bar 55 to have no vertical movement during practically one-half of the machine cycle and also for a short 100 period during the center of the other half-cycle, with a rapid upward movement preceding, and a rapid downward movement succeeding, respectively, the short stationary period. It will be understood that with 105 the needles neither rising or falling opportunity is afforded for readjusting the rows of thread guides so as to bring new threads within the path of the needles on either the hook or opposite side.

The throw on eccentric 29 may be altered by readjusting it on shaft 17 to time its action, as desired, in relation to that of cam 60. Instead of operating the bolsters 44 by an eccentric 29, a cam like cam 60 may be substituted so as to obtain any desired "dwell" in the horizontal movement of the needle bar. The movements of either the eccentric 29 or its substitute cam mechanism may be timed in any desired relation to the movements of cam 60, enabling the bringing about of any desired combination of movements and dwells of the needle bar in any vertical, horizontal or oblique path. All of these movements and dwells being 115 timed from main shaft 17, it follows that there can be no conflict of action but that 120 all the parts will work harmoniously.

It will thus be seen that by means of my 130 improved needle bar mechanism I am able

to move all the needles on the machine in planes parallel to each other at different times and in similar paths to those indicated in Figs. 12, 13, 14 and 15, as well as in an almost infinite variety of paths not illustrated, according to requirements of the lace or fabric being knitted. The needle hooks may be passed between the lower ends of the thread guides while the needles are progressing or receding or while they are rising or falling. It is also possible, by means of cams and eccentrics designed for the purpose, to delay any movement of the needle bar until the pattern chains have shifted the thread guide bars to extreme ranges of movement. Because of this exquisite control of the needle bar in relation to the shifting of the thread guide bars, the machine is adapted to produce fabrics and patterns of an almost infinite variety and at greatly increased speed and capacity for production.

Starting with the needle bar at the position indicated in Fig. 12 or at its lowest and rearmost position, when knitting certain fabrics any threads placed by the thread guide 85 across the paths of the rising and progressing needles 57 would only be engaged by the backs of the needles and could thus only be woven into the fabric by a binding action of other threads. In accomplishing this result the threads on a certain bar are placed across the path of the rising and progressing needles, causing the threads to be engaged by the backs and shanks of the needles. With the needles in forward and high position, another thread guide bar is moved by its pattern chain to bring a new series of threads across the path of the needles on their hook sides, so that the second thread series will be engaged by the hooks and looped into the fabric. The first series of threads are thus surrounded and bound into the fabric without their having actually been looped by means of the needle hooks. In certain other patterns the machine may cause every thread to be looped by first one needle and then by another, thus knitting each thread into the fabric instead of knitting some and binding the remainder. A high tension may be placed on some of the threads either bound or knitted in, and other threads may be given a loose tension, so that they will form an elastic loop or will even rise from the surface of the fabric in long projecting loops to be afterward treated by any desired process to produce a fur or nap. Such methods of knitting and fabrics produced thereby are set forth and claimed in certain other of my applications.

To illustrate one of the operations the machine may carry on, reference is made to Figs. 12 to 15. A small portion of finished work is shown at 141 and it will be seen that in Fig. 12 a loop 142 projects over the top

of the work plate 143 and is engaged by the hook 144 of needle 57. Loop 142 is a continuation of thread 140 which passes through the eye of thread guide 85. Thread 140' passing through thread guide 85' has been woven into the fabric 141 either by previous looping on one of the needles 57, or by being surrounded by a strand of thread 140. With threads 140 and 140' in this position, the needle 57 now rises and moves forward into the position shown in Fig. 13. Here it will be seen that loop 142 is on the shank of needle 57, below the latch 145. If thread guide 85 be now moved across the path of the returning needle 57, thread 140 will be engaged by the returning needle 57 (as in Fig. 14), and will be finally engaged by the needle hook as in Fig. 15. Here, it will be seen, the loop 142 is about to pass over the closed latch 145 and become incorporated in the fabric 141, while a new loop of thread 146 takes its place in the hook 144 to begin again the knitting process as in Fig. 12. In this process any threads 140' which are passed across the backs of the needles 57 by the thread guides 85' prior to the upward and advancing movement of needle 57 will be knit into the fabric by the threads 140, and may thus pass back and forth through the fabric, engaged first by one thread 140 and then by another, forming all the time lateral loops within or on the surface of the fabric. Such threads 140' need not be engaged by the needle hooks.

The latch wire 145' attached to the needle bar at 145" is used to prevent latches 145 from snapping up and closing as loop 142, Fig. 13, slips down over the end of the latch while needle 57 is rising.

What I claim is:

1. In a knitting machine, the combination with a bodily displaceable needle bar, of means mounting the needle bar for lateral bodily shifting, brackets or carriers supporting the needle bar, a rock shaft, rockers on said shaft which have slots that slidably receive the brackets, whereby movement of the rockers positively pushes the needle bar upwardly and pulls it downwardly, a main shaft, an adjustable or settable timing operative connection between said main shaft and the rock shaft, and a second adjustable or settable timing operative connection between said main shaft and said means for mounting the needle bar, said needle bar being thereby subject to the action of two actuating means both of which are timed and operated by the main shaft, both actuating means being positive in action, whereby the cycle of movement of the needle bar may be exactly predetermined by individual and relative adjustment of the timing connections aforesaid.

2. In a warp knitting machine, the combination with needles and thread guides, of

- substantially continuously-acting take-up means adapted to continuously take up the fabric under tension as it is knitted, and freely-spring-suspended tension rods acting on the warp threads between the warp beams and the thread guides.
3. In a warp knitting machine, the combination with a frame, needles and thread guides, of substantially continuously-acting take-up means adapted to continuously take

up the fabric under tension as it is knitted, coil springs attached to the frame, a connection between said coil springs, and tension rods for the warp threads, said rods being attached to, and freely suspended by the coil-springs, said tension rods acting on the warp threads between the warp beams and the thread guides.

In testimony whereof I affix my signature.
ISAAC SPRINGTHORPE.
